UNITED STATES PATENT OFFICE.

AUGUST S. HELD, OF FREEPORT, ILLINOIS.

DESIGN FOR A HINGE.

SPECIFICATION forming part of Design No. 24,137, dated March 19, 1895.

Application filed February 2, 1895. Serial No. 537,126. Term of patent 7 years.

To all whom it may concern:

Be it known that I, AUGUST S. HELD, a citizen of the United States, residing at Freeport, in the county of Stephenson and State of Illinois, have invented and produced a new and original Design for Spring - Hinges, of which the following is a specification.

Figure 1 is a plan view of the hinge when it lies upon that face which is to be applied to a door. Fig. 2 is an edge view, looking to the left in Fig. 1.

The hinge appears to consist of:—A base plate, A, A'; a central, approximately semi-cylindrical portion, D, raised above the plane of the plate and having its sides and ends equidistant, respectively, from the plate's corresponding margins; and, at each end of said portion, a tip, B, B', which resembles a half-

cone extending to the end of the plate and there terminating in a small ball C,—the metal of the plate being carried upward, nearly perpendicularly, to all marginal points of the half cylinder and half cone, so that the whole visible surface may be approximately continuous.

The central, or indispensable, feature of this design consists in a hinge having the conical tips within the marginal end outlines of the hinge.

What I claim is—

The design, for a hinge, herein shown and described.

AUGUST S. HELD.
